CLAIM

The ornamental design for a fishing rod vibration transfer ring, as shown and described.

DESCRIPTION

FIG. 1 is a top front perspective view of a vibration transfer ring in accordance with the new design;

FIG. 2 is a top rear perspective view thereof;

FIG. 3 is a top view thereof;

FIG. 4 is a front view thereof;

FIG. 5 is a rear view thereof;

FIG. 6 is a perspective view of FIG. 1 as it would appear prior to being secured to a fishing rod handle; and,

FIG. 7 is a perspective view of FIG. 1 as it would appear prior to being secured to a spinning fishing rod handle.

The broken lines shown in the drawings are only provided to illustrate the environment of the design and form no part of the claimed design.
